UNITED STATES PATENT OFFICE.

JAMES S. STEMONS, OF PHILADELPHIA, PENNSYLVANIA.

SOUNDING TOY.

1,368,855.

Specification of Letters Patent. Patented Feb. 15, 1921.

Application filed March 23, 1920. Serial No. 368,029.

To all whom it may concern:

Be it known that I, JAMES S. STEMONS, a citizen of the United States, residing at Philadelphia, in the county of Philadelphia and State of Pennsylvania, have invented certain new and useful Improvements in Sounding Toys; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of this invention is to provide a novel sounding toy of the whirligig type, rotatable in reverse directions to produce a sound, or noise.

20 The accompanying drawing clearly discloses the underlying principles of my invention. Briefly described—

Figure 1 is a face view, partly in section of one form of my invention,

25 Fig. 2 is a view taken looking at right angles to the plane of Fig. 1,

Fig. 3 is an edge view of a modified form.

Fig. 4 is a central vertical sectional view through a still further modified form of 30 the toy, and Fig. 5 is an enlarged detail view of a modified form of the invention.

Referring now in detail to the drawings, and first to Figs. 1 and 2:

1, 1 designate two disks, provided with 35 circumferential telescoping flanges 2.

Adapted to be seated between said disks is a core 3, circular in shape and disposed concentrically with respect to said disks 1, 1. The diameter of the core 3 is less than 40 that of the disks, so that there is a channel, or passage-way, 4 around said core. The core is provided with a circumferential recess, or notch, 5, in which is disposed a whistle 6 with the inlet end thereof disposed adjacent apertures 7, 7 in the flanges 2 of the disks 1. The exit end of said whistle is out of contact with the bottom 8 of said recess 5. Said whistle 6 is disposed out of contact with one of the side walls of 50 the recess 5, as shown, so that air passing through the apertures 7 enters the whistle through the inlet end thereof and escapes through the exit end, thence along said recess 5 to the outer end thereof, and thence 55 along the passage between the circumference

of the core 3 and the flanges 2 to exit openings 8, 8 in the flanges 2 of the disks 1.

Passing centrally through the core 3 and the disks 1, 1 is an axial pin formed at its exterior ends into eyes 9'. Cords 10 are attached to said eyes, one of said cords to each of said eyes, and furnish means whereby, when the cord is twisted and pulled upon, the disks 1 will be given a rapid rotary movement in one direction or the other, thus causing passage of air through the openings 7 to actuate the whistle 6. By alternately causing the cord to be twisted first in one direction and then in the other, the disks may be given rotary movement in reverse directions.

Auxiliary sound-producing means are provided, and such means are herein shown as comprising a plurality of whistles 9,—in this instance four,—carried by said shells 75 1, 1 and radially disposed with reference to the core 3. Obviously, as the shells are rapidly rotated, air passes through the whistles 9, thus augmenting the noise produced by the whistle 6, disposed interiorly 80 of said shells.

Referring now in detail to Fig. 3; showing a slight modification of my invention:

The only difference between this form and that shown in Figs. 1 and 2 is that the whistles 9 of the device of the preceding figures are omitted. In other respects, the device is precisely the same.

Referring now in detail to Fig. 4, showing a slightly further modified form of the 90 invention:

3' designates an annular core disposed interiorly of the disk 1'. Interiorly of the shells are secured, preferably to the flanges 2' thereof, clappers 11, 11, of spring material, having one end thereof 12, secured to the inner surface of the flange 2'. Each clapper 11 is bent adjacent said end 12, as shown at 13, so that the main portion of said member 11 is spaced from the flange 2'. Each clapper 11 is provided at its free end with a weight 14, disposed adjacent to and normally out of contact with a metallic member 15, secured to the disks 1'. Preferably, each member 15 is formed as an angle bar, one of the flanges thereof being secured to one of the disks 1', and the other flange being in the path of movement of the weight 14, as the clapper 11 vibrates back and forth.

The disks 1' are provided with the same means as shown in the devices of the preceding figures, namely cords, whereby in operation, when said cords are twisted and pulled upon said disks 1' will be rapidly revolved, whereby the vibration of the device and the flow of air in the annular passage vibrates the clappers 11, so that the heads 14 thereof strike alternately upon the metallic member 15 and the flange 2' of the disks. It will be understood, of course, that the disks 1' are of metal and that the clappers 11, 11 are also of metal. By striking against the flanges 2' of the disks, and against the metallic members 15, the clappers 11 produce a noise.

The device of Fig. 4 may, if desired, be provided with the whistles 9, shown in Figs. 1 and 2.

An important function of the core forming an element of all the species of my invention is that of a weight. Since the disks, between which said core or weight is disposed, are preferably of light sheet metal, it is desirable to provide auxiliary means for lending body, or weight, to the disks, so that they may be more easily revolved; such cores act as weights for the purpose indicated.

Having thus fully described my invention, what I claim to be new is:

1. A sounding toy, comprising two disks provided with telescoping circumferential flanges, a core disposed interiorly of said shells and concentric therewith, and of lesser diameter than said shells, forming an annular passage, sound producing means carried within said shells, and means for rotating said shells to create a flow of air within the passage to actuate said sound producing means.

2. A sounding toy comprising two disks provided with telescoping marginal flanges, a core disposed interiorly of said disks and of lesser diameter than said disks forming a passageway around said core, said core being provided with a circumferential recess, and sound-producing means disposed within said recess, said disks being provided with air-inlet and outlet openings.

3. A sounding toy comprising two disks provided with circumferential telescoping flanges, a core disposed interiorly of said disks and of lesser diameter than said disks, forming a passageway around said core, said core being provided with a circumferential recess, and sound-producing means disposed within said recess, said flanges being pro-

vided with air-inlet and outlet openings at diametrically opposite points.

4. A sounding toy comprising two disks, a core disposed interiorly of said disks and of lesser diameter than said disks forming a passageway around said core, said core being provided with a circumferential recess, and sound-producing means disposed against one wall of said recess and spaced from the opposite wall thereof, said disks being provided with air-inlet and outlet openings.

5. A sounding toy comprising two disks, a core disposed interiorly of said disks and of lesser diameter than said disks forming a passageway around said core, said core being provided with a circumferential recess, and a whistle disposed within said recess, said disks being provided with air-inlet and outlet openings.

6. A sounding toy comprising two disks provided with telescoping marginal flanges, a core disposed interiorly of said disks and of lesser diameter than said disks forming a passageway around said core, said core being provided with a circumferential recess, and sound-producing means disposed within said recess, said disks being provided with air-inlet and outlet openings, and a plurality of sound-producing members carried by said disks and radially disposed with reference to said core.

7. A sounding toy comprising two disks provided with telescoping marginal flanges, a core disposed interiorly of said disks and of lesser diameter than said disks forming a passageway around said core, said core being provided with a circumferential recess, and sound-producing means disposed within said recess, said disks being provided with air-inlet and outlet openings, and a plurality of whistles circumferentially carried by said disks and radially disposed with reference to said core.

8. A sounding toy comprising two disks provided with telescoping marginal flanges, a core disposed interiorly of said disks and of lesser diameter than said disks forming a passageway around said core, said core being provided with a circumferential recess, and sound-producing means disposed within said recess, said recess being provided with air-inlet and outlet openings, and means for rotating said disks to actuate said sound producing instrumentalities.

In testimony whereof I hereunto affix my signature.

JAMES S. STEMONS.
